AUTOMATIC CLOSING DISPENSING DEVICE
FOR COLLAPSIBLE TUBESCharles Stewart Mann, Vancouver, British
Columbia, Canada

Application September 27, 1937, Serial No. 165,782

8 Claims. (Cl. 221—60)

My invention relates to improvements in automatic closing dispensing devices for collapsible tubes. The objects of the invention are to provide a dispensing device for a collapsible tube which can be automatically closed against the extrusion of its contents by pressing a button; to provide for the device to be locked in closed position by turning in one direction and for opening by turning in an opposite direction. Further objects are to provide a novel form of dog by which the device is secured against rotation upon the nipple of a collapsible tube, said dog being displaceable without the use of screw driver or other tools to permit the device to be removed from one tube and for its replacement on another.

The invention consists essentially of a sleeve forming part of or being adapted for connection to the discharge end of a collapsible tube, an apertured cap capable of endwise movement along the sleeve to permit extrusion of the contents of the tube and a push button for effecting the closure of the apertures in the cap, as will be more fully described in the following specification and shown in the accompanying drawing, in which:

Fig. 1 is a vertical sectional view of the invention.

Fig. 2 is a fractionated plan view through the main sleeve taken on the line 2—2 of Figure 1.

Fig. 3 is an elevational view of the cylinder and latch.

Fig. 4 is an enlarged sectional view of the means for locking the device to the tube nipple taken on the line 4—4 of Figure 2.

Fig. 5 is an enlarged elevational view of the locking device.

Fig. 6 is a plan view of the invention taken on the line 6—6 of Figure 1 showing the approximate position of the bolt and push button when the device is in normal closed position.

In the drawing like characters of reference indicate corresponding parts in each figure.

The numeral 1 indicates a collapsible tube having shoulders 2 and a threaded nipple 3. Fitted upon the nipple 3 is a main sleeve 4 having a substantially conical base flange 5 which is adapted to fit the shoulders 2 of the tube 1 and an internal flange 6 which is drawn down onto a packing washer 7 placed between it and the end of the nipple. The sleeve 4 is provided with an annular packing ring 8 adjacent its upper end and is also provided with a pair of opposed peripheral grooves 9. The peripheral grooves 9 each consist of a horizontal run 10, see Figures 1 and 2, and an inclined run 11, and extending upwardly from the horizontal run, preferably adjacent its intersection with the inclined run, is a vertical groove 12. Mounted concentrically above the main sleeve 4 is a cylinder 13 having radial

arms 14 by which it is connected, in any suitable manner, to the main sleeve 4.

The cylinder 13 is provided with a vertical groove 15 having an opening 16 at its lower end extending through the cylinder wall and above the groove is a recess 17 in which a spring 18 is carried. Pivotaly mounted in the cylinder wall and partly in the groove 15 is a lever 19 having a latch 20 at its base projecting through the opening 16 and at its upper end a transversely arcuate thrust plate 21 which is urged outwardly by the spring 18.

Slidably and rotatably mounted upon the main sleeve 4 is a cap 22 having a cylindrical portion 23 at its base and a discharge opening 24 at or near its upper end. The cylindrical portion 23 is secured to the main sleeve by a pair of pins 25 which respectively enter the grooves 9 or the vertical groove 12, thus permitting the cap to turn without vertical movement to the extent of the horizontal runs 10, to turn with an endwise movement to the extent of the inclined runs 11 and to move endwise only to the extent of the vertical groove 12.

Fitted into the side wall of the cap is a spring retracted bolt 26 fitted with a push button 27. This bolt is adapted to be brought into alignment, when the cap is raised to its full extent, with the pins 25 in the inclined runs 11 of the grooves 9 with the thrust plate 21, so that by pressing the button the lever 19 is rocked to move the latch 20 radially outward.

Screwed into the base of the cylinder 13 is a plug 28 having a stem 29 upon which a coil spring 30 is freely mounted and slidably mounted in the cylinder is a hollow plunger 31 which is upwardly urged by the spring. The plunger 31 is provided adjacent its base with an annular groove 32 which is adapted to be entered by the latch 20 to prevent the plunger from rising within the cylinder 13. The upper end of the plunger 31 is provided with a tapered closure 33 for the discharge opening 24 and is fitted with a washer 34 which is compressed between the closure and the cylinder 13 when the cap 22 is in closed position as shown in Figure 1.

A locking device generally indicated by the numeral 35 and shown in detail in Figures 4 and 5 is provided to lock the sleeve 4 against turning on the nipple 3. This locking device consists of a cover plate 36 which is hinged in a recess 37 formed in the wall of the sleeve. The cover plate is provided on its inner side with a dog 38 having a cutting edge 39 which is adapted to be pressed into the soft metal of the nipple 3. A pin 40 extends from the cover plate and carries a coil spring 41 which abuts the base of a recess 42 and serves to relieve the lifting strain necessary to lift the cover plate and remove the dog 38 from engagement. The cover plate is adapted

to lie flush with the outer face of the sleeve 4 and to be fully exposed for opening, as in the position indicated in dotted lines in Figure 4, when the cap is raised and the pins 25 are at the upper 5 extremity of the vertical grooves 12 in the sleeve 4.

Having thus described the several parts of my invention I will now briefly describe its use.

When fitting the device to a new tube, the cap 22 is raised to its fullest extent and the pins 25 10 are in the upper extremity of the grooves 12, the sleeve 4 is then screwed onto the nipple 3 until the flange 5 is properly seated on the shoulders 2 of the tube. When in this position the cover plate 36 is pressed down to the position shown in Figures 2, 4 and 5, thus forcing the cutting edge 39 15 of the dog 38 through the opening 43 in the sleeve and into the metal of the nipple 3. Subsequent to the closing down of the cover plate the cap is moved downwardly and turned upon the sleeve 4 20 when the pins 25 will be riding in the horizontal portions 10 of the grooves 9, as shown in Figure 1.

To open the device in order to discharge some 25 of the contents of the tube, the cap 22 is turned, causing the pins 25 to ride along the inclined 30 portions 11 of the grooves 9, while the plunger 31, being retained in retracted position in the cylinder, permits the discharge opening to be uncovered; as soon as sufficient paste has been 35 discharged, pressure on the thumb button 27 will cause the bolt 26 to depress the arcuate plate 21 of the lever 19 and remove the latch 20 from the groove 32 of the plunger, thus allowing the closure 33 to be smartly thrust into the discharge opening and shut off the flow.

To lock the device against extrusion, the cap 40 will be turned in an opposite direction, which will cause the pins to ride down the inclined portions 11 and into the horizontal portions 10. This action restores the plunger to its former or retracted position where it is again held by the latch 20.

What I claim as my invention is:

1. A dispensing device for collapsible tubes 45 comprising a sleeve, a cap rotatable and endwise movable upon the sleeve, said cap having a discharge opening and a closure for the opening carried by the sleeve, means for holding the closure stationary within the sleeve when the 50 cap is moved outwardly endwise, a spring for urging the closure towards the opening in the cap, and means for releasing the spring.

2. A dispensing device for collapsible tubes 55 comprising a sleeve, a cap rotatable and endwise movable upon the sleeve, said cap having a discharge opening and a closure for the opening carried by the sleeve, said closure being endwise movable by a spring, and means projecting from the cap for releasing the spring to move the closure towards the openings.

3. A dispensing device for collapsible tubes 60 comprising a sleeve, a cap movable lengthwise of the sleeve, said cap having a discharge opening, a closure endwise movable within the cap, means for urging the closure towards the opening, and manual means operable from the exterior of the cap for releasing the closure to close the discharge opening.

4. A dispensing device for collapsible tubes 70 comprising a sleeve having a peripheral groove divided into a substantially horizontal portion

and an inclined portion, an endwise movable closure carried concentrically by the sleeve, a cap rotatable about the sleeve and having a discharge opening adjacent one end, a pin extending from the cap into said groove whereby when the pin is in the horizontal portion of the groove the cap is held with the discharge opening closed by the closure and as the cap is turned to bring the pin towards the free end of the inclined portion of the groove the discharge opening is moved away from the closure and a coil spring for projecting the closure longitudinally of the cap to close the discharge opening.

5. A dispensing device for collapsible tubes 15 comprising a sleeve, a cap rotatable and endwise movable upon the sleeve, said cap having a discharge opening, an endwise movable closure carried by the sleeve, means for urging the closure into the discharge opening, means for holding the closure in retracted position, means for moving the cap as it is rotated away from the closure to open the discharge opening, and means manually operable when the cap is away from the closure for releasing said closure from retracted 20 position to close the discharge opening.

6. In a dispensing device for collapsible tubes 25 having a sleeve adapted for attachment to the nipple of the tube and a cap slidably endwise upon the sleeve between predetermined limits 30 to open the device to discharge, said cap having a pin, and said sleeve having a cooperating groove for confining the outward movement of the cap upon the sleeve, said sleeve having an aperture, and a dog extending through said aperture for engaging the nipple to lock the sleeve thereto, said dog being held against removal from the aperture by the cap when the cap movement is confined.

7. In a dispensing device for collapsible tubes 40 having a sleeve adapted for attachment to the nipple of the tube and a cap slidably endwise upon the sleeve, between predetermined limits, to open the device to discharge, said cap having a pin, and said sleeve having a cooperating 45 groove for confining the outward movement of the cap upon the sleeve, said sleeve having an aperture, and a complementary recess, a dog hinged within the recess and extending through the aperture to engage the nipple, said dog being held against disengagement from the nipple by the cap when the cap movement is confined.

8. In a dispensing device for collapsible tubes 55 having a sleeve adapted for attachment to the nipple of the tube and a cap slidably endwise upon the sleeve, between predetermined limits, to open the device to discharge, said cap having a pin, and said sleeve having a cooperating groove for confining the outward movement of the cap upon the sleeve, said sleeve having an aperture, and a complementary recess, which recess is partially covered by the cap at any point of its confined endwise movement, a cover plate hingedly mounted in the sleeve and a dog on the cover plate extending through the aperture to engage the nipple, the outer surface of the cover plate being adapted to lie approximately flush with the outer periphery of the sleeve whereby the dog is held in extended position by the cap.
